UNITED STATES PATENT OFFICE.

HENRY R. MERSELES, OF BRONXVILLE, NEW YORK, ASSIGNOR TO HERBERT E. MERSELES, OF BRONXVILLE, NEW YORK.

WASHING MACHINE.

Application filed September 16, 1921. Serial No. 501,110.

To all whom it may concern:

Be it known that I, HENRY R. MERSELES, a citizen of the United States, residing at Bronxville, in the county of Westchester 5 and State of New York, have invented certain new and useful Improvements in Washing Machines, fully described and represented in the following specification and the accompanying drawings, forming a part of 10 the same.

This invention relates to improvements in washing machines and particularly machines designed for the washing of dishes and similar articles, and is directed to increasing 15 the efficiency of such machines while permitting a simplification in their construction.

An important object of the invention is to provide a washing machine with a rotary 20 projector adapted to project water or other washing medium upon all sides of the articles to be washed, in the course of its rotation. The rotary projectors heretofore used in dish washing machines have been 25 provided with rearwardly inclined nozzles from which the washing medium was projected upon the articles to be washed, the reaction from the jets from these nozzles being utilized to rotate the projector. Some 30 rotary projectors have been provided with axially directed nozzles in addition to the rearwardly inclined nozzles. Such rotary projectors project the washing medium against the edge of the articles to be washed 35 and against one side of the articles during their rotation. Such a rotary projector, however, cannot project water directly against all sides of the articles.

A washing machine incorporating the 40 present invention is provided with a rotary projector located adjacent to a rack in which the articles to be washed are supported. The projector has rearwardly inclined discharge openings and forwardly inclined discharge 45 openings directed toward the articles in the rack. As the projector rotates the washing medium projected from the forwardly inclined discharge openings impinges upon the opposite side of the articles from that projected from the rearwardly inclined discharge openings, so that in the course of each 50 rotation of the projector the washing medium is discharged against all sides of the articles. The rotation of the projector is

most desirably caused by reaction of the 55 washing medium projected, and may be obtained either by so locating the forwardly and rearwardly inclined discharge openings which project the washing medium against the dishes that the reactive movement of the 60 sprays from the rearwardly inclined openings is greater than that of the sprays from the forwardly inclined openings, or by providing rearwardly inclined discharge openings in addition to the openings used to project the washing medium upon the articles, 65 to furnish a reactive force to rotate the projector. A washing machine incorporating the invention and provided with a single rotary projector has been found to have a 70 washing efficiency substantially equal to that of a washing machine containing two oppositely placed rotary projectors of the type heretofore used.

Other objects and advantages of the 75 invention are hereinafter explained.

In order that the invention may be clearly understood I will describe in detail the specific embodiments of it illustrated in the accompanying drawings, in which:—

Fig. 1 is a front elevation of a dish washing machine with a portion of the tank broken away to disclose the washing mechanism;

Fig. 2 is a fragmentary front elevation of 85 the washing machine, showing the rotary projector turned through an angle of 90° from the position shown in Fig. 1;

Fig. 3 is a similar fragmentary front elevation showing the rotary projector turned 90 through an angle of 180° from the position shown in Fig. 2;

Fig. 4 is a top view of the rotary projector and the top of the pump casing;

Fig. 5 is a side elevation of the rotary 95 projector and its mounting, sectioned on the lines 5—5 of Figs. 6 to 9;

Figs. 6, 7, 8 and 9 are enlarged transverse sections of the rotary projector taken upon the lines 6—6, 7—7, 8—8 and 9—9 of Fig. 100 5 respectively; and

Fig. 10 is a top view, and Fig. 11 an end view, of a rotary projector of modified construction.

The washing machine illustrated 105 comprises a receptacle or tank 10 and dish washing mechanism which includes a motor 11 supported below the bottom of the tank 10

and a centrifugal pump 12 located in the lower portion of the tank 10 and driven by the motor 11. In the discharge neck 13 of the pump 12 is mounted the rotary projector 20. Supported in the tank 10 above the rotary projector 20, is a rack 14 in which dishes 15 or other articles to be washed may be placed. A pipe 17 is provided for introducing water or other washing medium into the tank 10 and for withdrawing the same therefrom.

The construction of the rotary projector 20 is best shown in Figs. 4 to 9. In the form illustrated in these figures the projector 15 has an integral tubular body 21 forming two diametrically opposite radial wash arms 22, 23. The outer ends of the arms 22, 23 are closed by end pieces 24, 25. While these end pieces may, if desired, be made integral 20 with the tubular body 21, certain advantages hereinafter explained are obtained by making the end pieces separate and adjustably securing them to the ends of the tubular body 21 by means of set screws 26.

25 On the lower side of the tubular body 21, at a point intermediate its ends, is an intake opening 27 which is internally threaded. Into the opening 27 is screwed a hollow hub 28 which is rotatably mounted in the discharge neck 13 of the casing of the pump 12. It is apparent that if desired the hub 28 may be made integral with the tubular body 21, although, in order to form a bearing surface upon the hub, it has been found 30 more convenient to make the hub separate.

It is desirable to mount the hub 28 in the discharge neck 13 in such manner that it may easily be removed therefrom. As best seen in Fig. 5, the hub 28 is rotatably 40 mounted in a collar 29 which is removably secured in the neck 13 by means of a screw 30 which passes through the neck and enters a recess 31 in the collar 29. At the lower edge of the hub 28 is an external annular 45 flange 32 which engages the lower edge of the collar 29 so as to prevent the hub 28 from being raised in the collar 29 by the force of the water entering the rotary projector from the pump.

50 In order to secure smooth flowing and proper distribution of the water entering through the opening 27, the upper wall of the tubular body 21 is extended inwardly so as to form a deflector 34 above the 55 opening 27.

Along the upper sides of the arms 22, 23 are formed discharge nozzles 41, 42, 43, 44, 45, 46, the nozzles 42 to 45 being formed upon the tubular body 21, and the nozzles 60 41, 46 being formed on the end pieces 24, 25. In the end of each nozzle is a discharge opening having the form of a slot 47 which extends longitudinally of the arms, that is to say, radially of the rotary projector. The 65 interval width of the nozzles to their ex-

treme outer ends is much greater than the width of the discharge slots 47 so that the rate of flow of the water passing outwardly through the nozzles is much less than the rate at which the water is projected through 70 the discharge slots. As a result, the water emerges from the slots 47 in flat fan-shaped sprays.

The nozzles and their discharge openings are inclined to the axis of rotation of the 75 projector 20 (i. e., the axis of the hub 28). Certain of the nozzles and openings are rearwardly inclined so as to project water rearwardly as the projector rotates while others of the nozzles and openings are forwardly inclined so as to project water forwardly as the projector rotates. In the specific form illustrated the projector, for a reason hereinafter explained, rotates in a clockwise direction looking from the top, 80 and the nozzles 41, 44, 45, 46 are rearwardly inclined with respect to such rotation while the nozzles 42, 43 are forwardly inclined. The nozzles are most desirably all inclined to the axis at the same angle. In the form 85 illustrated the nozzles are so arranged that all of them except the end nozzle 41 project their fan-like sprays in a common plane inclined to the axis of rotation of the projector.

90 It is apparent that the reaction of the sprays from the rearwardly inclined nozzles 41, 44, 45, 46 tend to cause the projector to rotate in a clockwise direction while the reaction of the sprays from the forwardly 95 inclined nozzles 42, 43 tend to retard such rotation. The nozzles are so positioned that the reactive moment of the sprays from the rearwardly inclined nozzles is greater than the reactive moment from the sprays from 100 the forwardly inclined nozzles and the entire projector is, therefore, caused to rotate in a clockwise direction by reaction.

105 If a more rapid rotation of the projector than that obtained by the difference in the reactive moment of the sprays from the nozzles arranged as shown in Figs. 1 to 9 is desired, the end pieces 24, 25 may be adjusted about the ends of the tubular body 110 so as to incline the nozzles 41, 46 rearwardly at a greater angle than that at which the other nozzles are inclined. Or, by inclining the nozzle 41 in the opposite direction from that shown, anti-clockwise rotation of the projector may be obtained.

115 It should be noted that in the form shown in Figs. 1 to 9, no two of the nozzles are at the same distance from the axis of rotation of the projector. The nozzles are spaced from the axis in the following order: 44, 43, 120 45, 42, 46, 41; the nozzle 44 being the nearest to the axis and the nozzle 41 being the farthest therefrom. This unsymmetrical arrangement of the nozzles has the advantage of causing each nozzle to rotate in a 125 130

different circle, thus giving the most even possible distribution of the washing medium over the dishes. The particular arrangement of the nozzles shown, however, necessitates making the arm 22 longer than the arm 23. The tubular member 21 is formed to provide a weight 48 on the arm 23 which counterbalances the longer arm 22 making the center of gravity of the rotary projector

10 at or near the axis of the hub 28.

In the operation of the machine described, the lower portion of the tank 10 is filled with hot soapy water or other washing medium and the motor 11 is then operated to 15 drive the pump 12 which draws water from the bottom of the tank and forces it into the tubular body 21 through the opening 27. The washing medium is projected from the discharge slots of the nozzles in flat fan-like sprays extending radially of the projector and inclined to the axis of the projector. As the projector rotates, the sprays from the forwardly inclined nozzles 42, 43 20 strike upon the articles against which washing medium was projected from the rearwardly inclined nozzles 46, 45, 44 half a revolution before; but the sprays from the forwardly inclined nozzles 42, 43 strike the opposite side of these articles from that 25 against which the washing medium was projected by the rearwardly inclined nozzles 46, 45, 44. Thus, during each complete revolution of the projector the fan-like sprays are swung around so as to strike every side of 30 the dishes 15, or other articles supported in the rack 14. This operation is illustrated in Figs. 1, 2 and 3. Thus, in Fig. 1, where the arm 22 is shown extending to the right, the arm 23 to the left, the sprays projected from 35 all the nozzles except the end nozzle 41 are inclined toward the observer striking the side of the articles away from the observer. When the projector has rotated through an angle of 90° so that the arm 22 is toward the 40 observer as shown in Fig. 2, the sprays from all the nozzles, except the end nozzle 41, are inclined to the left striking the right side of the articles. On a further rotation of 90°, the sprays from all the nozzles, except the 45 end nozzle 41, are inclined in the opposite direction to that shown in Fig. 1, so that they strike the side of the articles toward the observer. A still further rotation of 90° brings the arm 23 toward the observer as 50 shown in Fig. 3, and the sprays from all the nozzles, except the end nozzle 41, are then projected to the right striking the left side of the articles. It should, of course, be understood that the 90° points are mentioned 55 merely for the sake of illustration, there being a continuous change in the direction in which the sprays are projected against the articles as the projector rotates.

From the above description of the operation of the washing machine it is apparent

that the greater part of the washing is done by the water projected from the nozzles 42, 43 and the nozzles 46, 45, 44 which because of their inclination in opposite directions project the washing medium against all sides 70 of the articles. The nozzle 41 may be regarded as a driving nozzle, although it has also an important washing function, particularly at the corners of the rack 14.

While the embodiment of the invention 75 which has been described has proved extremely efficient in practice, it should be clearly understood that the invention is by no means limited to this specific embodiment of the invention. Thus the staggered arrangement of the nozzles is not essential to the carrying out of the invention. In Figs. 10 and 11 is illustrated a modified form of rotary washer in which the arms 22' and 23' are of the same length and the corresponding nozzles of each arm are at equal distances from the axis of rotation. It is apparent that in this arrangement the reactive moment of the sprays from the nozzles 42', 43' is just balanced by the reactive moment 80 of the sprays from the nozzles 45', 44'. In this case a rotation of the washer is caused by the end nozzles 41', 46' both of which may be inclined as illustrated in Figs. 10 and 11 so as to cause anti-clockwise rotation, 85 or if desired, may be inclined so as to cause clockwise rotation, of the projector.

Furthermore, it is not essential that the forwardly inclined nozzles and rearwardly inclined nozzles be arranged to project 100 sprays in a common plane, nor is it necessary that all the nozzles inclined in the same direction be located adjacent to each other, nor that the body of the projector have the form of radial arms.

It should be understood that the expressions "forwardly inclined" and "rearwardly inclined" in the claims following relate to inclination with respect to the axis of rotation of the projector, in directions forward or rearward with respect to the direction of rotation of the projector, it being, of course, immaterial whether this direction of rotation is clockwise or anti-clockwise. The precise number of the forwardly inclined discharge openings or nozzles or of the rearwardly inclined discharge openings or nozzles is a matter which may be varied to suit particular conditions, and it should be understood, therefore, that where the words 110 "discharge openings" or "nozzles" occur in the claims these words include the use of a single discharge opening or nozzle, except in instances where a plurality of openings or nozzles is expressly specified.

Certain features of the washing machine illustrated form part of the subject matter of the co-pending application of Herbert E. Marseles, Henry R. Marseles, Charles F. Simmons, and Paul H. Engel, 120 125

filed May 5, 1921, Serial No. 467,046, and are in consequence not claimed in this application.

What is claimed is:

5. 1. In a washing machine, a single rotary projector, and means for supporting the articles to be washed about the axis of the projector at one side thereof, the side of the projector adjacent to said support being provided with discharge openings inclined to the axis of the projector, some of said openings being inclined forwardly with respect to the direction of rotation of the projector so as to project the washing medium directly against a side of the articles as the projector rotates, and others of said openings being inclined rearwardly with respect to the direction of rotation of the projector so as to project the washing medium directly against the opposite side of the articles as the projector rotates. 75
10. 2. A washing machine as claimed in claim 1, in which the discharge openings of the projector are so located that the moment of reaction of the washing medium discharged through the rearwardly inclined openings exceeds that of the washing medium discharged through the forwardly inclined openings, so that the projector is rotated by 80
15. 30 the resultant reaction of the washing medium discharged through the openings. 90
3. In a washing machine, a rotatably mounted projector having in one of its sides an axial inlet opening, means for forcing washing medium into said projector through said inlet opening, and means for supporting the articles to be washed about the axis of the projector at the opposite side of the projector from said inlet opening, the side 95
35. 40 of the projector adjacent to said support being provided with discharge openings inclined to the axis of the projector and so arranged that the resultant reaction of the washing medium discharged therethrough causes a rotation of the projector, certain of said discharge openings being inclined forwardly with respect to the direction of rotation of the projector and having the form of narrow radial slots so as to project 100
45. 50 a sheet of washing medium directly against one side of the articles as the projector rotates, and others of said openings being inclined rearwardly with respect to the direction of rotation of the projector and having the form of narrow radial slots so as to project 105
55. 60 a sheet of washing medium directly against the opposite side of the articles as the projector rotates. 110
4. In a washing machine, a projector having an inlet opening, means for forcing washing medium into said projector through said inlet opening, means for supporting the articles to be washed at the opposite side of the projector from said inlet opening, the side of the projector adjacent to said 115
- 65 support being provided with a plurality of discharge openings formed and arranged to project a sheet of washing medium in a common plane extending diametrically across the projector and across the article support, and means for rotating the projector about an axis lying at an angle to said plane and passing through the article support. 120
5. In a washing machine a rotary projector, and means for supporting the articles to be washed about the axis of the projector at one side thereof, the side of the projector adjacent to said support being provided with nozzles having blunt ends inclined forwardly with respect to the plane of rotation of the projector and each containing a narrow arcuate discharge slot extending radially of the projector and adapted to project a flat fan-like spray of washing medium against one side of the articles as the projector rotates, and nozzles having blunt ends inclined rearwardly with respect to the plane of rotation of the projector and containing narrow arcuate discharge slots extending radially of the projector and adapted to project flat fan-like sprays of washing medium against the opposite side of the articles as the projector rotates. 125
6. In a washing machine, a projector comprising a rotatably mounted hollow hub portion and a plurality of hollow radial arms extending therefrom, means for forcing washing medium into said arms through said hub, and means for supporting the articles to be washed about the axis of said hub at one side of said arms, said projector being provided with a discharge opening located near the end of one of said arms and rearwardly directed so that the reaction of the washing medium projected therethrough causes a rotation of the projector and with a plurality of other discharge openings located along the side of said arms adjacent to said article support, certain of said openings being inclined forwardly with respect to the direction of rotation of the projector so as to project the washing medium directly against one side of the articles as the projector rotates, and the others of said openings being inclined rearwardly with respect to the direction of rotation of the projector so as to project the washing medium directly against the opposite side of the articles as the projector rotates. 130
7. In a washing machine, a support for the articles to be washed, a rotary projector comprising a hollow hub rotatable about an axis passing through the article support, and a pair of diametrically opposite radial arms of different lengths extending from said hub adjacent to the article support, the longer of said arms being provided with a discharge opening adapted to project the washing medium against the portion of the 135

- articles furthest from the axis of the hub, and the shorter of said arms being provided with a discharge opening adapted to project the washing medium against a portion 5 of the articles located nearer the axis of the hub and with a weight adapted to counter-balance the longer arm so that the center of gravity of the projector is at or near the axis of the hub.
- 10 8. A rotary projector for washing machines, comprising a tubular member forming a pair of diametrically opposite radial arms and having discharge openings along one side thereof and an inlet opening intermediate its ends in the opposite side
- 15 thereof, and a transverse deflector projecting toward the middle of said inlet opening from the opposite side of the tubular member and adapted to direct substantially equal portions of the liquid introduced 20 through said inlet opening into said arms, respectively.
- In testimony whereof I have hereunto set my hand in the presence of two subscribing witnesses.

HENRY R. MERSELES.
